LIGHTING FIXTURE

David Ruskin, Perth Amboy, N. J.

Application March 22, 1954, Serial No. 29,630

Term of patent 7 years

(Cl. D48—23)

To all whom it may concern:

Be it known that I, David Ruskin, a former citizen of Lithuania, residing at Perth Amboy, in the county of Middlesex and State of New Jersey, have invented a new, original, and ornamental Design for a Lighting Fixture, of which the following is a specification, reference being had to the accompanying drawing, forming a part thereof.

In the drawing:

I claim:

The ornamental design for a lighting fixture, as shown.
